UNITED STATES PATENT OFFICE.

HENRY BENSON LAMBERT, OF PARISH OF ST. HELENA, LOUISIANA.

PLOW.

SPECIFICATION forming part of Letters Patent No. 601,516, dated March 29, 1898.

Application filed August 18, 1897. Serial No. 648,652. (No model.)

To all whom it may concern:

Be it known that I, HENRY BENSON LAMBERT, of the Sixth ward, in the parish of St. Helena and State of Louisiana, have invented 5 a new and useful Improvement in Plows, of which the following is a full, clear, and exact description.

The object of my invention is to provide a plow so constructed that the point and the 10 landside may be raised and lowered one independently of the other and whereby the handle of the plow may be likewise independently raised and lowered.

A further object of the invention is to provide 15 a peculiar form of stock, which stock will consist of side members adjustable on the beam and a main member pivoted between the side members and capable of forward and rear movement on the beam, the main member of 20 the stock being adapted to carry the share.

A further object of the invention is to improve the plow in the details of its construction, rendering the same much more simple and durable and the plow in its entirety more 25 effective than the majority of plows of its type.

The invention consists in the novel construction and combination of the several parts, as will be hereinafter fully set forth, and pointed out in the claims.

Reference is to be had to the accompanying 30 drawings, forming a part of this specification, in which similar characters of reference indicate corresponding parts in all the figures.

Figure 1 is a side elevation of the improved 35 plow. Fig. 2 is a plan view, and Fig. 3 is a bottom plan view, of said plow. Fig. 4 is a vertical longitudinal section illustrating the locking device for the stock and the locking device for the connecting medium between the 40 stock and the landside.

The stock A is preferably made shorter than the ordinary stock, and the handles B are pivotally attached to the stock, one at each side in the customary manner, the pivot-bolt for 45 the handles being designated by the numeral 10. The aperture for the bolt 10 in the beam is small and horizontally elongated, so that the handles may be adjusted backward and forward. The clevis consists of a horizontal 50 bow-section 11, having a series of apertures 14 made therein, the bow-section being firmly attached to the beam and a pivot-section 12,

likewise of bow construction, held to travel over the fixed section 11, carrying a pin 13, which may be entered into any one of the 55 apertures 14, as may be found desirable in plowing and to change the direction of the plow or carry the team away from the path of the share.

The stock C is of peculiar construction. It 60 comprises two side arms 15 and 16, which are curved downwardly and forwardly, and a central main arm 17. All three of the arms are connected near the bottom by means of a bolt 18, provided with a suitable head and a lock- 65 nut. The upper ends of the outer arms 15 are adjustably attached to the beam through the medium of a bolt 19, apertures 20 being made in the beam to receive the said bolt, so that the stock through the medium of these outer 70 arms may be raised or lowered at will.

The intermediate or central arm or section 17 of the stock is of such length as to enable it to extend upward through the stock A, an opening 30 being vertically made in the stock 75 for the reception of this arm or section, and the said stock is elongated or of such length as to permit of the central section or arm 17 of the stock being moved forwardly or rearwardly, so as to depress or raise its lower 80 portion. The upper end of the central arm or section 17 of the stock is reduced and exteriorly threaded to receive a washer 28 and a lock-nut 29, the lock-nut and washer acting in the capacity of a set-screw and permitting the said central section or arm of the stock to be secured wherever it may be adjusted. 85

Two uprights 20^a are located at the rear of the implement, one at each side of the beam. 90 The lower ends of these braces are forwardly and downwardly curved and are pivoted to the outer arms 15 of the stock C by a pivot-bolt 20^b. The upper ends of the uprights are made to diverge and are carried one to an 95 engagement with the outer face of each handle B. Each upright at or near its center is provided with a series of openings or apertures 21, and the two uprights are pivotally connected to the beam by passing a bolt 22 100 through registering apertures in the uprights and a suitable aperture in the beam, as shown in Fig. 1. The upper ends of the uprights are adjustably connected with the handles B,

and to that end are provided with a series of apertures 23, a bolt 24 being passed through the two handles and registering apertures in the uprights, the said bolts being preferably provided with two nuts at each end, one engaging with the inner face of a handle and the other with the outer face of the upright bearing against the handle. Under this construction it will be observed that the handles will be raised or lowered, as desired, and that the uprights may be carried bodily upward or downward, so as to regulate the position of the side arms or sections 15 and 16 of the stock C.

15 A landside D is pivoted at its forward end between the sections of the stock, preferably by the pivot-bolt 18, connecting the bottom of said sections, and an adjusting-bar 25 is pivotally attached to the inner face of the landside at its free end, the said adjusting-bar being preferably round, so as not to obstruct the passage of the earth, and this adjusting-bar is carried upward between the uprights 20 and through an opening 26 made in the beam A. The upper portion of the adjusting-bar is threaded, and nuts 27 27^a are placed on the threaded portion of said adjusting-bar 25, bearing against the top and bottom faces of the beam.

30 The landside is reinforced at the rear portion of its outer or wearing face by an attached bar 33. Therefore the wear of the landside is on the attached bar 33, which may be removed and replaced by a perfect one when worn out. A flange 32 is secured to the forward edge of the lower portion of the central section of the arm 17 of the stock, as shown in Figs. 1 and 3. The plowshare and point 31 are bolted or otherwise secured 35 to this flange, the share shown in the drawings being that of a turn-plow. The central arm or section 17 of the stock is at its lower end made of such width, as shown in Fig. 3, as to fill the space between the forward portion of the landside D and the left-hand outer member of the stock.

When the central or main section or arm 17 of the standard C is moved forward, it will throw the point of the plow down and the 40 point or forward end of the beam up, thus causing the plow to take the ground in a manner to plow well in grass and trash where ordinary plows would choke. The peculiar construction of the standard also enables the operator to run dull and worn points with 45 ease and to so shorten the traces that the horse will travel close to the plow.

The adjusting-bar 25 enables the operator to raise or lower the landside to suit the character of the ground being plowed, and as the bar is round in cross-section it will catch very little dirt. The standards 20^a, as heretofore stated, enable the handles to be raised and lowered, and also enable the stock C and landside to be carried bodily forward or rearward, the adjusting-bar 25 of the landside

being capable of sufficient movement in the beam to admit of such manipulation.

The peculiar construction of the clevis will enable the operator to give the plow more or less land and to plow close to corn, cotton, &c., while the horse walks at one side of the line of the furrow to be made by the plow.

Having thus described my invention, I claim as new and desire to secure by Letters Patent—

1. The combination, with a plow-beam, of a stock comprising three sections or arms, the outer sections or arms being pivoted one to each side of the plow-beam, the central 80 arm or section having vertical and lateral movement in the plow-beam, all the sections or arms of the stock being pivotally connected at their lower ends, for the purpose set forth.

2. The combination, with a plow-beam, of 85 a stock comprising three arms or sections, the outer arms or sections being adjustably pivoted to the plow-beam, one at each side, the three arms being pivotally connected near their lower ends, and the intermediate arm 90 or section having vertical and lateral play in the beam, a fastening device for the central section of the stock, and means, substantially as described, for attaching a plowshare to the said central section of the stock, as and for 95 the purpose specified.

3. The combination, with a plow-beam, of a stock composed of two outer and an intermediate arm or section, the outer sections or arms being pivotally attached at their upper 100 ends to the beam, one at each side, all of the sections being pivotally united near their lower ends, the intermediate section or arm being adjustable vertically and longitudinally of the plow-beam, a locking device for 105 the intermediate section or arm, a landside having its forward end held between the sections of the stock, and an adjusting-bar pivoted to the rear end or heel of the landside and adjustably carried through the beam, 110 and a locking device for the adjusting-bar of the landside, for the purpose set forth.

4. The combination, with a plow-beam, of a stock constructed in three sections or arms, the outer sections being pivotally attached 115 to the beam, one at each side, the three sections being pivotally connected at their lower ends, the central section or arm having lateral and vertical movement in the plow-beam, a locking device for the said central section 120 or arm, a landside having its forward end pivoted between the sections of the stock, an adjusting-bar pivoted to the rear end or heel of the landside and adjustably carried through the beam, a locking device for the adjusting-bar of the landside, a reinforcing-bar secured 125 to the wearing-surface of the landside, and a flange projected from the forward edge of the central section or arm of the stock, the said flange being adapted to receive and support a share, as and for the purpose specified.

5. In a plow, the combination, with a beam,

handles pivoted to the beam, and a stock comprising three arms or sections, the outer ones being pivotally attached to the beam at each of its sides, the central arm or section having vertical or lateral movement in the beam, and the lower ends of all three sections of the stock being pivotally connected, of a landside pivoted at its forward end between the sections of the stock, an adjusting-bar pivoted to the heel of the landside and adjustably located in the beam, uprights pivoted to

the beam and adjustably connected with the handles and pivoted to the outer sections of the stock, and locking devices for the adjusting-bar of the landside and the central section of the stock, all being combined for the purpose specified. 15
